UNITED STATES PATENT OFFICE.

HENRI HERNU, OF MEUDON, FRANCE.

GAS GENERATOR.

Application filed July 2, 1920. Serial No. 393,674.

(GRANTED UNDER THE PROVISIONS OF THE ACT OF MARCH 3, 1921, 41 STAT. L., 1813.)

To all whom it may concern:

Be it known that I, HENRI HERNU, a citizen of the French Republic, residing at Meudon, S. and O., in the French Republic, 5 have invented new and useful Improvements in Gas Generators (for which I have filed an application in France, Patent No. 493,681, Dec. 9, 1918), of which the following is a specification.

10 My invention relates to gas generators, and it is my object to produce a gas generator with compensated vaporization and temperature. In gas generators as at present used, various processes are adopted to supply vapor to the hearth, consisting notably:

1. In placing a vaporizer above the fire (a type having a refractory hearth);
2. In surrounding the hearth by a double casing containing water (a type having a 20 metallic hearth lined, or not, with refractory materials);
3. In simultaneously using both arrangements by placing a vaporizer at the base and another above the hearth.

25 None of these arrangements insure an uniform or constant composition of gas for very variable deliveries such as those particularly required for motor vehicles.

In order to enable the principle, on which 30 the generator constructed according to this invention is based, to be understood, it is useful to examine the phenomenæ which occur in the hearth of the generator during variations of gas supply required by the 35 motor of a vehicle.

The hearth is divided in two superposed parts, the lower portion forms zone of reaction of the oxygen and vapor on the carbon, while in the upper zone is produced 40 the partial distillation of the fresh coal.

In a well designed apparatus, the lower or reaction zone should be capable of using up or burning nearly all the oxygen or air admitted to the hearth during normal working of the motor, while in the upper part slow combustion occurs by reason of the small quantity of oxygen which escapes from the reaction zone.

If a larger supply of gas is required, the 50 greater velocity of air drawn through the lower part of the hearth will no longer admit of nearly complete reaction, so that an excess of free oxygen reaches the upper

part the temperature in which becomes immediately raised by the now activated combustion therein. It is therefore in the median and upper parts of the hearth where the temperature varies sensibly with the fluctuations in the production of the gas, while the lowermost zone must remain practically invariable to insure a constant composition of gas. For this purpose it is necessary that the quantity of the vapor reaching the base of the hearth should always be proportional to the volume of gas generated.

The invention is shown by way of example, in the accompanying drawing in vertical section through the axis of a generator embodying the principles hereinbefore stated, said generator being connected with a motor not shown for driving a vehicle.

As will be seen from the drawing, the generator comprises a hearth whose outer 75 part A is furnished with refractory material B resting on a crown C the lower portion of which may be constructed so as to form a quick vaporizer at the moment of lighting.

The part B of the hearth forms what may be termed a cup-shaped reaction crucible situated above a dished fire-grate or grid.

The upper part D' forms the vaporizer which surrounds the hearth and comprises 85 a dipping cone-shaped collar D^x situated above the hearth to realize one of the principles stated.

In fact the lower cylindrical portion D of the vaporizer D' which surrounds the hearth in the upper distillation zone causes the vaporization to vary by reason of the temperature of this zone, which temperature is directly due to the variations of the volume of gas withdrawn as stated above; on the other hand, that part of the vaporizer which forms the collar D^x above the hearth recovers a portion of the calories drawn off by the gas and promotes in conjunction with the surrounding portion D, a rapidly varying vaporization. The steam vapor thus produced maintains a nearly constant temperature in the lower part of the hearth, that is to say in the reaction zone.

This vapor passes, through the intermediary of a down-tube E into a horizontal chan-

nel F communicating with the atmosphere at its opposite end G whose size of opening can be regulated by a shutter H.

The channel F forms, at its centre, an annular conduit I which places it in communication with radiating channels J, formed, for facility of construction, in the arms of a grid-carrying receptacle K; these channels can likewise be formed of radiating tubes 10 leading out at the periphery of the receptacle K which is fitted with a suitable grid or dished fire-grate K^x.

The receptacle K is carried by a shaft L whose height is regulated from outside by a screw threaded stem and handwheel M actuating a bellcrank lever M', or by any other appropriate means whereby vertical displacement of this receptacle can be obtained.

A plate N connected with the receptacle K, 20 forms a valve whose seat K¹ is constituted by the upper extremity of the conduit I.

This arrangement permits the air admitted, around the periphery of the receptacle K, to the hearth to be perfectly saturated 25 by reason of the arrival in opposite directions of air and steam vapor, which two fluids become thoroughly mixed in the conduit I before their passage through the hearth. This condition is indispensable to 30 obtain a uniform distribution of heat in the lower part of the hearth in order to obtain a gas of homogeneous composition.

The air saturated with steam-vapor is directed towards the periphery of the grid K^x, 35 when the plate N rests on the conduit I, or saturated air in variable proportions can pass upwards between the arms K¹ of the receptacle K and through the interstices of the grid according to the amount of lift of 40 the receptacle K and plate N above the conduit I. Gas required for driving the motor (not shown) is drawn off through a pipe V connected with the upper part of the hearth beneath the collar D^x of the vaporizer.

45 It is of capital importance that the coal should not escape from the grid through the vibrations of the vehicle.

For this purpose a guard O, either plain or pierced and of suitable form, cylindrical, 50 conical, spherical, etc., surrounds the grid-carrying receptacle K and can be raised into the position, indicated by dotted lines, by

means of a lever P, or by any other appropriate mechanical means.

Finally the arrangement is completed by 55 a fuel-feeder forming cover to the vaporizer and having an internal closing plate Q for the charging opening carried by an arm R integral with an external controlling rod S. Closing pressure, is obtained by a central spring T which uniformly distributes the force over the whole periphery of the closing plate Q, while the reaction of the spring T upon its seat in the arm R also insures the closing of the upper cover U 60 65 which is fast on the rod S and moves horizontally in conformity with the plate Q and arm R. It will be clear that any provision of fuel carried in the supply chamber W can be intermittently discharged into the fuel 70 storing room Y above the hearth.

I claim:

1. A gas generator divided into a furnace zone, a reaction zone, and a vaporizing zone, and consisting in a dished firegrate, a superposed cup-shaped reaction crucible having a refractory lining and an upwardly increasing diameter, an annular vaporizer with a dipping cone-shaped collar seated on said crucible, a fuel-feeder forming cover and fuel supply chamber to the hearth, a steam outlet from the vaporizer integral with the covering fuel-feeder, pipe-connection from said outlet to the underside of the fire-grate and opening to the atmosphere, and a gas- 75 80 85 delivery beneath said cone-shaped collar.

2. In a gas generator, divided into a furnace zone, a reaction zone, and a vaporizing zone, a furnace, a dished fire-grate therein, a grate-carrying receptacle formed of hollow radiating conduits for distributing a mixture of steam and gas towards the periphery of the grate only and forming a valve, and means connected with the base of the said receptacle formed valve for distributing the mixture over the whole surface of the grate. 90 95

3. In a gas generator divided into a furnace zone, a reaction zone, and a vaporizing zone, a furnace, a dished fire-grate therein, and a vertically displaceable guard surrounding the grate to retain the fuel. 100

HENRI HERNU.
